UNITED STATES PATENT OFFICE.

EMIL A. CLAUS, OF NEW YORK, N. Y.

SHELL-FUSE.

1,186,282.

Specification of Letters Patent.

Patented June 6, 1916.

Application filed August 24, 1915. Serial No. 47,069.

To all whom it may concern:

Be it known that I, EMIL A. CLAUS, a citizen of the United States, and a resident of the city of New York, borough of Brooklyn, 5 in the county of Kings and State of New York, have invented a new and Improved Shell-Fuse, of which the following is a full, clear, and exact description.

My invention relates to combination fuses. 10 An object thereof is to provide a simple, inexpensive and efficient fuse the detonation of which is accomplished either by the firing of a time fuse or by the impact of the shell or projectile with which the fuse is provided.

15 A further object of the invention is to produce a simple and effective combination fuse or projectile which will allow the same to be handled with safety and insure to the shell when it is fired certain detonation of the explosive charge at a predetermined time or upon impact of the shell.

With the above and other objects in view, the nature of which will more fully appear 20 as the description proceeds, the invention consists in the novel construction, combination and arrangement of parts as herein fully described, illustrated and claimed.

In the accompanying drawings, forming 25 part of the application, similar characters of reference indicate corresponding parts in all the views.

Figure 1 is a longitudinal section through a shell or projectile provided with a fuse embodying my invention; Fig. 2 is a top plan view of the shell; Fig. 3 is a transverse section on line 3-3, Fig. 1; Fig. 4 is a similar section on line 4-4, Fig. 1; Fig. 5 is a transverse section on line 5-5, Fig. 1; Fig. 6 is a similar section on line 6-6, Fig. 1; and Fig. 7 is a perspective view of the frangible strip.

Referring to the drawings, 8 represents a housing of the shell; into the front end 45 of which a bushing 9 is threaded. The bushing 9 has uniformly spaced bores 10, the axes of which are parallel with the axis of the bushing. The bores 10 are open at the top of the bushing wherethrough a priming 50 cap 11 can be introduced into each bore and secured to the bottom of the bore by any suitable means, as shown, by a clamping ring 12 which wedges the cap to the walls of the bore at the bottom thereof. U-shaped, 55 frangible strips 13 are suspended from the

top of the bushing into each bore. The ends of the frangible strips are bent laterally to rest on the top of the bushing, so that the bottom of each strip is spaced from the priming cap 11 located at the bottom of the 60 bore. A firing pin 14 is provided in each of the bores. The ridges 15 of the pin maintain the same concentric with the bore. The ridges of the pin engage the bottom of the frangible strip 13, with the pointed end 16 65 of the pin projecting through the bottom.

A headed ignition sleeve 17 is secured to the bushing 9 by a retaining flanged nipple 18. A fuse ring 19 is rotatably mounted on the ignition sleeve 17, and it is prevented 70 from longitudinal displacement on the sleeve by the head of the ignition sleeve and the flange of the nipple 18, said flange of the nipple clamping the ends of the frangible strips to the top of the bushing. The 75 surface of the flange clamping the frangible strips is provided with a circular groove 20 which establishes communication between all of the bores 10, and which also forms 80 seats for the coil springs 21 which retain the firing pins 14 on the bottom of the frangible strips. The flange of the nipple 18 has an aperture 22 which establishes communication between the circular groove 20 and the recess 24 for the fuse of the fuse ring 19. 85 The fuse ring 19 has an opening 23 which leads to a circular groove 25 in the head of the sleeve 17. A slot 26 on the outer surface of the sleeve connects the groove with a chamber 27 in the bushing 9, the chamber 27 being in communication with the interior 90 of the shell 8.

The headed sleeve 17 carries a bushing 28, the bottom of which is provided with an opening 29 establishing communication between said bushing and the chamber 27 of the bushing 9. A frangible strip 30 is suspended in the bushing 28 from the top thereof. The strip supports a firing pin 31, the ridges 32 of which form the guides for the pin in the bushing 28. The frangible strip is clamped to the sleeve by a tip 33 which is secured to the bushing 28. The tip carries a priming cap 34 which is maintained by said tip normally in contact with the 105 point of the firing pin 31.

When a shell, provided with a fuse as described, is fired from a gun, the firing pins 14 will break the frangible strips 13 and explode the priming caps 11, setting the 110

fuse in the fuse ring 19 on fire. The discharge of the shell from the gun will also cause the firing pin 31 to break the frangible strip supporting it and move against the bottom of the bushing 28. The time fuse is set at a proper distance, which is determined by the displacement of the ring 19 relative to the opening 22 in the flange of the sleeve 18. Normally the opening 22 in 10 the flange is maintained under the bridging portion 35 of the fuse recess 24 in the fuse ring 19. An accidental displacement of the opening 22 from under the bridge 35 is prevented by a spring-actuated pin 36, 15 provided in the fuse ring 19, engaging a recess in the flange of the sleeve 17. An effort is required to displace the fuse ring 19 from its normal position. When the fuse in the recess 24 is set on fire, the same 20 will burn until it reaches the opening 23 in the fuse ring, when the fire is transferred by the circular groove 25 to the longitudinal groove 26 and the chamber 27, causing the shell to explode. If for any reason the shell 25 did not explode at the time set, or the shell has met with an obstacle, the impact of the shell meeting the obstacle, or when falling on to the ground will cause the firing point 32 to strike the priming cap 34, setting the 30 chamber 27 on fire and thus causing the explosion of the shell.

From the above it will be seen that with my combination fuse, if the shell fails to explode at a proper time set, it will explode 35 either if the shell meets an obstacle before the time fuse is to explode the shell or after, if it did not explode then. It may also be remarked that if the shell did not explode at the impact, it will explode when the burning fuse ring 19 reaches the opening 23.

While I have described the principle of operation, together with the device which I now consider to be the best embodiment thereof, I desire to have it understood that 45 the device shown is merely illustrative and that such changes may be made as are within the scope of the appended claims.

I claim:

1. A shell fuse, comprising a bushing 50 having a plurality of symmetrically-disposed bores, a priming cap in each bore, a spring-impelled firing pin in each of said bores, a frangible strip spacing the firing pin from the cap in the bore, means clamping said frangible strips to the bushing, time-fuse carrying means associated with said clamping means and adjustable relative thereto, said clamping means having means for establishing communication between the 55 fuse and the bores in the bushing, said frangible strips being adapted to rupture when the shell is discharged, thus setting the fuse 60

on fire, and means establishing communication between the fuse and the shell.

2. A shell fuse, comprising a bushing 65 adapted to communicate with the interior of the shell, a firing pin in said bushing, a frangible strip maintaining the pin a pre-determined distance from the bottom of the bushing, a tip clamping the strip to the 70 bushing, and a priming cap carried by said tip and maintained thereby in close proximity to the firing pin, said frangible strip being adapted to rupture when the shell is discharged, whereby the pin is moved 75 against the bottom of the bushing, the impact of the shell causing said firing pin to strike the priming cap whereby the shell is exploded.

3. In a shell fuse, a bushing having a 80 plurality of symmetrically-disposed bores, a firing cap in each bore, a spring-impelled firing pin in each bore, a frangible strip in each of the bores spacing the pin from the cap, a flanged nipple secured to the bushing, 85 the flange of said nipple clamping the strips to the bushing, a headed sleeve secured by said nipple to the bushing, a time-fuse ring rotatably mounted on the sleeve between the flange of the nipple and the 90 head of the sleeve, said flange of the nipple having a circular groove establishing communication between all the bores and an opening from the groove to the fuse of the fuse ring, said fuse ring having an opening 95 to the head of the sleeve, said head of sleeve having a circular groove registering with the opening in the fuse ring and a longitudinal groove on the sleeve extending from the circular groove in the head into the 100 bushing, said frangible strips adapted to rupture at the discharge of the shell, whereby the fuse is ignited, a bushing secured to said sleeve and communicating with the first-mentioned bushing, a firing pin in 105 said second bushing, a frangible strip spacing said pin from the bottom of the second bushing, a tip clamping the frangible strip to said bushing, and a priming cap carried by said tip and maintained in close proximity to the firing pin, said frangible strip adapted to rupture when the shell is discharged, whereby the pin is brought against the bottom of the second-mentioned bushing, 110 said pin adapted to fire the cap when the shell strikes an object.

In testimony whereof I have signed my name to this specification in the presence of two subscribing witnesses.

EMIL A. CLAUS.
